UNITED STATES PATENT OFFICE.

EDWARD P. TRESE, OF BAY CITY, MICHIGAN.

SMOKE TRAP.

Application filed March 15, 1924. Serial No. 699,427.

To all whom it may concern:

Be it known that I, EDWARD P. TRESE, a citizen of the United States of America, and a resident of Bay City, in the county 5 of Bay and State of Michigan, have invented certain new and useful Improvements in Smoke Traps, of which the following is a specification.

This invention relates to smoke traps and 10 the like and particularly to a smoke trap for use in furnaces and heating plants of like nature.

The prime object of the invention is to 15 pivotally mount a smoke trap in the fuel passage so that when the fire door is opened for charging the furnace, smoke and gas will not escape through the opening.

Another object is to provide a smoke trap 20 and means whereby it can be secured in raised position for the insertion of a bar through the fire door opening to remove clinkers or for other purposes.

A further object is to design a very simple, substantial and inexpensive smoke trap, 25 which swings up when a shovelful of coal is placed in the furnace, and automatically drops back to position when the shovel is withdrawn.

With the above and other objects in view, 30 the present invention consists in the combination and arrangement of parts, herein-after more fully described, illustrated in the accompanying drawings and particularly pointed out in the appended claims, it being understood that changes may be made 35 in the form, size, proportion and minor details of construction without departing from the spirit, or sacrificing any of the advantages of the invention.

40 In the drawings.

Fig. 1 is a side view of a heating furnace showing my improved smoke trap in place.

Fig. 2 is a fragmentary sectional side view of the fire door and fuel passage, the smoke 45 trap being shown in position therein.

Fig. 3 is a similar view showing the smoke trap in raised position.

Fig. 4 is a fragmentary top plan view of the fuel passage and smoke trap.

50 Fig. 5 is an isometric view of the smoke trap plate.

When charging a furnace or other heating plant the fire door is opened and the coal or fuel shoveled in through this fuel 55 passage or opening, which allows smoke and gases to escape through this opening, and

this is particularly noticeable when a furnace has been in operation for a time, and considerable soot adheres to the smoke passage and flues. This disagreeable feature I 60 have overcome by providing means in the fuel passage opening for automatically closing the passage when the shovel is withdrawn, the shovelful of fuel forcing it up to allow the fuel to be shoveled into the 65 firepot and dropping of its own weight when the shovel is withdrawn.

Referring now particularly to the drawing, in which I have shown the preferred embodiment of my invention, the numeral 70 5 indicates a conventional hot air furnace, and while in the present instance I have shown a hot air furnace, it will be obvious that it is equal adaptable for steam, hot water and other types of heating plants. 75

A flat plate member 6 is pivotally hung to the door frame which forms a part of the fuel passage 7, and is provided with openings 8 therein and by means of which the plate is hung on the turned end of the 80 bolt members 9 which are secured to the top wall of the fuel passage, these are formed substantially similar to an eye bolt, the end being threaded and adapted to receive a nut in the usual manner, the other 85 end having an open eye to allow the plate to be hung thereon, the other end of the plate being free and hanging at an angle in the passageway to form a closure therefor. By securing to the door frame, the 90 device can be installed on furnaces which are set up and jacketed, it being merely necessary to drill the two openings as shown.

For holding the plate in raised position to allow for unobstructed access to the interior of the furnace, a clip member 10 is pivotally secured to the upper wall of the fuel passage by means of the bolt 11, this member normally being turned to position as indicated in dotted lines in Fig. 4 of 100 the drawings, but when it is desired to hold the smoke trap in raised position, this clip is turned to position as shown in Fig. 3 of the drawing.

The provision of the clip for holding the 105 plate member in raised position is both inexpensive and satisfactory, but it will be understood that this may be accomplished in various ways.

From the foregoing description it will be 110 obvious that I have perfected a very simple, effective and economical smoke trap for pre-

venting the escape of smoke and gases through the fire door. operable means for holding said door in raised position.

15

What I claim is:—

1. The combination with a furnace having an elongated fuel entrance passage leading thereto, a flat door mounted within said passage to swing entirely therein, and forming a closure for said passage.

2. The combination with a furnace having an elongated fuel entrance passage leading thereto, a flat door mounted within said passage to swing entirely therein, and forming a closure therefor, and manually

3. The combination with a furnace having an elongated fuel entrance passage leading thereto, a flat door mounted within said passage to swing entirely therein, and forming a closure therefor, and a clip pivotally connected to the wall adjacent the said plate, and adapted to hold the door in raised position.

20

In testimony whereof I hereunto affix my signature.

EDWARD P. TRESE.
